UNITED STATES PATENT OFFICE.

DAVID ZAIDEN, OF NEW YORK, N. Y.

MECHANICAL EYES.

1,373,785.

Specification of Letters Patent. Patented Apr. 5, 1921.

Application filed October 13, 1919. Serial No. 330,329.

To all whom it may concern:

Be it known that I, DAVID ZAIDEN, a citizen of the Russian Government, and residing at New York, New York county, and 5 New York State, have invented certain new and useful Improvements in Mechanical Eyes, of which the following is a specification.

This invention relates to mechanical eyes 10 for dolls and the like and its object is to provide pivotal means for the eyes which are easily alined, adjusted and located in the head of the doll so that the position and motion of the eyes will be correct.

15 Other details and objects of the invention are more fully described in the following specification, set forth in the appended claim and illustrated in the accompanying drawings, wherein:

20 Figure 1 is a vertical sectional view through the head of a doll looking toward the front of the same,

Fig. 2 is a side view of the frame carrying the eyes,

25 Fig. 3 is a front view of the same.

In mounting mechanical eyes on the frame which carries and operates them and securing the same in the sockets of the doll's head, great difficulty is experienced in so 30 locating them that they are alined and properly fit the sockets so that the eyes are identically in position and move in unison.

The sockets are rarely identical and the frame often becomes bent and dislocates one 35 of the eyes, and after a great deal of work and patience it is found that, when finally located in the doll's head, the eyes are not yet true.

In the present invention the frame for 40 carrying the eyes 5, consists of the vertical rod 6, carrying the weight 7, and whose upper end 8, constitutes a spring to resist the sudden rear movement of the weight and the excessive movement of the eyes.

45 A cross bar 9, which is substantially U-shaped, carries on each end 10, one of the eyes 5, being embedded in the cement with which the eyes are filled. It is evident that

in hasty work that these ends are not identically located in the eyes so that the pupils 50 may differ in their location when fitted in the socket and one be higher or lower than the other.

In each eye and on its outer side is drilled a small socket, care being taken that they 55 are on the line of the two pupils, and into these sockets are placed the horizontal ends 11, of small brackets 12, preferably made of wire and loosely fitted so that the eyes are free to rotate thereon. The brackets 60 have rings 13 at their upper ends and when the eyes are properly located in the sockets, the brackets are cemented to the head on the inside by means of the rings and a suitable cement putty or wax. 65

This operation may be promptly performed and the brackets may be relied upon to securely hold the eyes in place when once located.

The weight 7, is fitted with a rubber buffer 70 14, at its front end as usual to protect the inside of the head.

It is obvious that the parts may be otherwise arranged or modified without departing from the essential features above described or from the scope of the appended 75 claim.

What I claim as new is:—

In mechanical eyes, the combination of 80 eyes carried at the ends of a horizontal bar and having sockets at their outer edges, a vertical resilient rod attached to the cross bar and comprising a spring at its upper end and carrying a muffled weight at its lower end, and hooks adapted to enter the 85 sockets and be fastened to the sides of the interior of a doll's head.

In testimony whereof, I have signed my name to this specification in the presence of two subscribing witnesses, this 27th day of 90 September, 1919.

DAVID ZAIDEN.

Witnesses:

DAVID SNYDER,
JAMES F. DUHAMEL.
